DESIGN FOR A COAT

Charles Goldstein, New York, N. Y.

Application June 19, 1940, Serial No. 93,113

Term of patent 3½ years

To all whom it may concern:

Be it known that I, Charles Goldstein, a citizen of the United States, residing in New York city, in the county of New York and State of New York, have invented a new, original, and ornamental Design for a Coat, of which the following is a specification, reference being had to the accompanying drawing, forming part thereof.

Fig. 1 is a front view of a coat showing my design;

Fig. 2 is the rear view of Fig. 1.

I claim:

The ornamental design for a coat, substantially as shown.

CHARLES GOLDSTEIN.
